Application September 21, 1936, Serial No. 101,700

17 Claims. (Cl. 221—95)

Our invention relates in general to dispensing apparatus and has more particular reference to apparatus for the dispensation of fluid, such as gasoline, although the invention may have more 5 general application; and our present application comprises a continuation in part of our co-pending application for Letters Patent of the United States on an improvement in Dispensing apparatus, Serial Number 633,563, filed September 17, 10 1932, Patent No. 2,059,442.

An important object of the present invention is to provide apparatus for the dispensation of fluids through a preferably flexible dispensing hose which, when not in use, may be housed entirely within a casing forming a part of the dispensing apparatus in concealed position.

Another important object is to mount the flexible fluid dispensing hose in position normally retracted completely within a housing, the hose 20 mounting equipment permitting the same to be drawn from the housing into dispensing position when dispensation of the liquid is to be accomplished; a further object being to form the housing with improved closure elements for covering 25 the opening through which the hose may be drawn from the housing when the apparatus is not in use; a still further object being to provide cover means for said opening adapted to be securely locked up to prevent unauthorized tampering with the dispensing hose.

Another important object is to provide dispensing apparatus of the character mentioned wherein the entire apparatus, including the housing, is adapted for overhead mounting as on the 35 ceiling of a building structure or automobile service station.

Another important object is to provide apparatus, including a reel for carrying the flexible dispensing hose when the same is in retracted, 40 inoperative position, including switch means cooperatively associated with the reel and operable to prevent dispensation of fluid through the hose when the same is in retracted position on the reel; a further object being to constitute the 45 switch means to automatically condition the dispensing apparatus for operation as and when the hose is unwound from the reel.

These, and numerous other important objects, advantages, and inherent functions of the invention, will become apparent as the same is more 50 fully understood from the following description, which taken in connection with the accompanying drawings discloses preferred embodiments of the invention.

55 Referring to the drawings:

Figure 1 is a diagrammatic view of a fluid dispensing system embodying our present invention;

Figure 2 is an enlarged view of a part of the apparatus shown in Figure 1;

Figure 3 is a perspective view illustrating a portion of the apparatus shown in Figures 1 and 2;

Figure 4 is a perspective view showing a modified form of the structure shown in Figure 3;

Figure 5 is a perspective view illustrating another embodiment of our present invention;

Figure 6 is a sectional view taken substantially along the line 6—6 in Figure 5;

Figure 7 is a perspective view of a hose supporting element forming a part of the equipment shown in Figures 1, 2, 5 and 6;

Figures 8 and 9 are sectional views taken substantially along the lines 8—8 in Figure 7 and 9—9 in Figure 8 respectively;

Figure 10 represents an elevation of a modification of the dispensing apparatus with parts 20 broken away;

Figure 11 is a rear elevation of the hose reel shown in Figure 10;

Figure 12 is an end elevation of the hose reel partly in section on line 12—12 of Figure 11;

Figure 13 shows the switch operating means of this modification; and

Figure 14 shows the nozzle receptacle of this modification in detail.

To illustrate our invention we have shown, on 30 the drawings, a fluid dispensing device including a preferably flexible fluid dispensing conduit or hose 11 terminating in a preferably valve controlled dispensing nozzle 13, and means to force fluid to and through the hose under pressure for 35 the purpose of dispensing the same. The fluid forcing means may comprise any suitable equipment, but we prefer to employ a pump 15 driven by any suitable or convenient motive means, the operation of which may be quickly and easily controlled and to this end we prefer to drive the pump by means of an electric motor 14.

In the illustrated embodiment, the intake of the pump 15 is connected by means of a conduit 17 with a storage tank 21 forming a reservoir 45 of fluid to be dispensed. The outlet of the pump 15 is connected by means of a conduit 19 with an air release and overflow device 23 having a vent 25 to atmosphere for discharging any gas 50 collecting in the device 23 and an overflow return conduit 27 connected with the storage tank 21. The overflow and air release device 23 is or may be connected by means of a conduit 31 through suitable metering devices 32 in the hous- 55

ing or standard 28 and through the sight gauge 33 to the hose 11.

It will be noted that the pump and its driving motor, that is to say, the equipment for forcing the fluid to the hose 11 under pressure, are shown located in the building 35 at a point remote from the housing 29. The fluid forcing means, of course, may be located in the housing 29, if desired, and of course the fluid may be delivered 10 from the tank 21 to the hose 11 by any suitable or preferred means other than the motor driven pump shown. In any event, it is desirable to control the operation of the fluid forcing means so that the operator may start and stop the same by 15 manipulating the dispensing hose as a part of the dispensing operation.

To this end the hose, while the apparatus is inactive, is adapted for mounting in concealed condition within the housing, but may be withdrawn 20 from the housing into dispensing position and we provide means automatically actuated by the withdrawal of the hose to concealed position in the housing in order to start the fluid forcing means in operation. Likewise, we provide means 25 which will automatically cause the hose to be retracted into the housing at the end of the dispensing operation as soon as the hose is released by the operator. The retraction of the hose automatically functions to discontinue operation of 30 the fluid forcing means. Any suitable hose mounting may, of course, be employed but we prefer to utilize a reel 37 located within the housing and on which the hose may be coiled when not in use. This reel preferably comprises 35 a tubular axle element 39 which may suitably comprise a length of pipe. The opposed ends of the pipe 39 are preferably sealed by plugs 41 threaded therein and said sealed ends are or may be rotatably supported in the casing 29 as by 40 means of the bearings 43 mounted on the inner opposite walls of the housing. The pipe 29 has means 45 fixed thereon forming a support on which the hose may be coiled, the means 45 preferably comprising a framework forming a 45 substantially cylindrical drum 47 or equivalent 50 hose receiving framework. The hose reel 37 also is preferably formed with a conduit 49 extending radially from and connected with the pipe 39, said conduit 49 being connected with the pipe 39 at 55 one end by means of the coupling 51. The other end of the conduit 49 extends outwardly of the hose carrying portion 47 and is provided with a neck 53 extending substantially at right angles with respect to the conduit 49.

55 One end of the hose 11 is secured to the neck 53 so that by rotating the drum in one direction the remainder of the hose may be coiled thereon in one direction, as indicated by the arrow 55 in Figure 7. The remainder of the hose may be 60 coiled on the reel. Means is provided for normally urging the hose reel to rotate in a direction to so wind the hose upon the reel and to this end we provide preferably on the pipe 39 a pulley 57 on which may be coiled a flexible driving cable 59, 65 one end of which is connected on the pulley and the other end of which is secured to an end of a spring 61, the opposed end of which is anchored on the housing. Obviously any other suitable drum urging means may be employed. The pipe 70 75 outwardly of the hose supporting means 45 is formed with a lateral opening 63 and the portion of the pipe containing said opening is surrounded by means forming a chamber 65, said chamber-forming means having openings 67 in the opposed walls thereof through which the pipe 39 extends.

Annular seals 69 are provided in position encircling the pipe 39 to seal the openings 67 around said pipe. The seals 69 may be of any suitable character, but we prefer to utilize seals comprising annular cup-shaped elements having surfaces adapted to set upon the walls of the chamber 65 around the openings 67, packing material 71 being arranged in the cup-shaped elements around the pipe 39 and held in place by washers. A spring 73 is or may also be provided 10 to urge the washers oppositely along the pipe whereby to compress the sealing material 71 in the cup-shaped elements and to urge the cup-shaped elements into sealing engagement with the walls of the housing 65 around the openings 15 67. The housing 65 has an inlet opening connected with a pipe 75 forming a part of the system for delivering fluid under pressure through the sight gauge 33, said pipe 75 being connected to the discharge of said sight gauge. 20

When the device is in operation, fluid will be delivered under pressure through the sight gauge, thence through the pipe 75, and into the chamber 65, from whence it may penetrate through the opening 63 into the pipe 39. From the pipe 25 39, the fluid may be forced through the radial conduit 49 and into the hose 11.

The dispensing nozzle 13 preferably has a manually operable control valve 93, operable by means of the handle 95. As heretofore mentioned, the reel 37 is normally urged in a direction, by means of spring 61 and the cable 59, to maintain the hose in coiled position on the reel, the hose thus being normally retracted and housed completely within the casing 29. Casing 29, however, has an opening 77 through which the hose may be drawn out of the housing, thus uncoiling the same from the reel and causing the reel to rotate during the uncoiling operation against the tension of the spring 61. The housing is also formed at the opening as shown at 79 to form a socket or sheath for receiving the nozzle 13 when the hose is in retracted position. 35

Cover means 81 is or may be provided for covering the sheath, said cover means comprising a hinged element as shown in Figures 3 and 6 or as shown in Figure 4 said cover means may comprise a pair of sliding door elements 83. Any suitable or convenient form of cover, however, may be utilized for the purpose of enclosing the opening and enclosing the nozzle socket. In addition, we prefer to provide cooperating means on the casing and on the door element as shown in Figures 3 and 6 or the cooperating door elements as shown in Figure 4 for the purpose of locking the same in closed position in order to prevent unauthorized tampering with the dispensing nozzle and hose when the apparatus is not in use. 55

In the case of the apparatus of Figures 5 and 6, the nozzle, due to the arrangement of cover 81, the action of gravity and flexure of the hose, will project itself from the housing as is clearly shown in Figure 5 when the lock is removed, so that it may readily be grasped by the operator. 60

As shown in Figure 3, the locking means 85 may comprise a perforated projection 87 on the housing in position to penetrate an opening 89 formed on the door element so that when the door element is closed the same may be secured 70 by means of a padlock 85 or other suitable fastening device. In the embodiment shown in Figure 5, the locking means may comprise adjacent perforated projections 87' and 89' through the perforations of which a padlock 85 or other suit- 75

able locking device may be inserted. In the embodiment shown in Figure 4, the relatively slideable door elements 83 may be formed with co-operating perforated projections 91 through the perforations of which a padlock 85 or other suitable fastening device may be inserted when the doors are in relatively closed position.

The nozzle 13 is preferably provided with a normally closed control valve 93 which may be opened by manually depressing a valve handle 95, forming a part of the said nozzle. It is ordinarily desirable to set the fluid forcing apparatus in operation prior to the manipulation of the handle 95 in opening the valve 93 in order that the hose may be substantially completely filled with fluid under pressure when the valve is opened and to this end our invention contemplates the provision of means for starting the fluid forcing equipment in operation automatically as the hose is retracted from the housing 29 and while any suitable mechanism may be employed for this purpose, we prefer to utilize switch means 95', preferably a sealed mercury switch mounted in position within the housing 29 to cooperate with the hose reel whereby the switch may be moved to open position by the rotation of the hose reel in a direction to wind the hose thereon, said switch being shiftable by rotation of the hose reel in the opposite direction, that is to say, in the direction caused by drawing the hose from the casing into dispensing position, to circuit closing position. The switch 95' is connected with the conductors 97 forming a circuit for the control of the fluid forcing mechanism, said control circuit being adapted when closed at the switch 95' to start and maintain the fluid forcing apparatus in operation, and being adapted when the circuit is broken at the switch 95' to immediately discontinue operation of the fluid forcing means. In order to operate the switch 95' as aforesaid, we provide a cam-like projection 99 on the rotatable hose reel, said projection being formed preferably on the pipe 39 outwardly of the hose supporting position 45. The switch 95' also is preferably mounted in a tilting bracket 101 having an arm 103 extending in the path of movement of the projection 99. Spring means 105 may be provided to resiliently hold the bracket 101. The bracket 101 may thus be tilted to either of two positions depending upon the direction of rotation of the pipe 39. In one position, the switch 95' will be closed and in the other open, and spring means 105 may be provided to yieldingly secure the bracket in both of said tilted positions. The arm 103 preferably has non-positive connection with the bracket 101 to permit the arm to yield and allow the projection 99 to pass repeatedly in one direction.

The embodiment illustrated in Figures 5 and 6 is essentially similar to the embodiment shown in Figures 1 and 2 except that the form of the casing 29 is modified in order that the casing, the hose reel, and the metering equipment may be mounted in over head position by securing said casing, for example, on the ceiling of a service station. In such an arrangement the feature of our present invention which resides in the coiling of the hose on the reel entirely within the housing when not in use is of particular importance for the reason that overhead mounting may be accomplished only where provision is made for disposing of the hose when the apparatus is not in use, the nature of the apparatus and the fluid dispensed thereby making it imperative to eliminate dangling hoses containing

flammable liquid such as gasoline. The provision of dispensing apparatus of the character mentioned adapted for overhead mounting is particularly useful in that valuable ground or floor space may thus be conserved to best advantage. 5 Moreover, by providing for the complete enclosure of the hose when not in use, the appearance of the dispensing equipment is considerably improved and the danger of damage to the hose is substantially eliminated for the reason that the same is entirely enclosed and completely protected except when being used in dispensing operations.

Referring to the accompanying drawings relating to Figures 10 to 14, inclusive, a housing 129 serves to enclose the lower portion of the dispensing apparatus which comprises the usual fluid pump 115, connections whereby it may be driven by an electric motor 117, to pump fluid from an underground reservoir (not shown) through the suction line 121, into an air release mechanism 119. From the latter mechanism the fluid passes through a combined check and relief valve 122, through a meter 123, through a conduit 125 to a sight glass or flow indicator 127 mounted outside 25 of the pump housings and thence through conduit 131 to the horizontal conduit 245 later to be described.

A clock or indicator mechanism 133 adapted to be controlled by the meter to register the volume, cost, price, etc., of the measured fluid is provided. This mechanism may be of any desired construction.

Superposed upon housing 129 is a housing 241 which overhangs the lower housing as indicated 35 at 135. Said housing 241 serves to enclose the hose reel, the hose nozzle, the motor switch and its operating means.

The conduit 245 mentioned above serves as an axle for supporting the reel 243. Support 137 40 serves to sustain part of the weight of the reel, hose and conduit 245. Suitable bearings 139 may be provided on said conduit to reduce the friction between it and the reel. Any desirable packing 141 may be provided to seal the joint 45 between the reel hub 145 and the axle or conduit 245. A cap 143 seals the hub of the reel at the side opposite to that by which the conduit enters it. If desired, shaft 245 may be provided with a trunnion 153 which may cooperate with 50 a support 137' similar to support 137 to increase the rigidity of the construction.

Hub 145 is provided with a radially extending conduit 147 by which the fluid passing from conduit 245 through opening 149 may be led to the 55 hose connection 151 and thence into the hose 111 and nozzle 113.

To provide for automatically returning the hose to stored condition within the housing, the reel is provided with a flange 155 to which is attached one end of a spiral spring 157 as shown at 156. The other end of this spring is hooked over or otherwise fastened to a lug 159 on a lever 161 which is pivotally mounted on the shaft 245. The lever 161 is provided with a threaded opening which is adapted to receive a cap screw 163. The capscrew projects through an arcuate slot 165 in the support 137' so that the lever may be angularly adjusted with respect to said support. The lever may be provided with a handle 167 to 70 facilitate the adjustment of the spring tension.

The reel is provided with an outer hub 171 which extends between the flanges 169 at a sufficient distance from the periphery thereof to receive approximately three coils of hose.

One of said flanges 168 is provided with a plurality of openings 172 adapted to receive a cap-screw 173 to hold the switch operating lug or cam 249 on said flange. The various openings 172 are provided so that the angular position of the cam may be changed to vary the time at which the switch is operated as will be disclosed below.

The switch 253 may be of any desirable vapor proof or hermetically sealed type. For purposes of illustration, a mercury switch is disclosed in the drawings. This switch comprises an arm 251 which is pivoted at 175 to a fixed portion of the apparatus, which supports at its lower end the mercury tube 177 and at its upper end the operating levers 179 and 181 which are pivoted at 183. The pivot 175 is of such nature that the lever 251 will be frictionally maintained in any angular position it may be forced to assume.

20 The levers 179 and 181 are provided with ears 185 and 187 respectively, which engage the edges of lever 251 from which the respective levers project. Springs 189 and 189' are respectively anchored at each end upon ears 191 and 193 of the levers and upon the arm 251 so that the ears 185 and 187 are maintained in engagement with the edges of lever 251. Levers 179 and 181 are of such length that they project into the path of the cam or lug 249.

25 30 The overhanging housing 241 is provided with a projecting channel 195 which is adapted to receive all but a portion of the nozzle 113 as the hose is reeled up and stored in the housing. A portion 197 of the nozzle spout projects beyond the channel to serve as a hand hold whereby the operator may withdraw the hose for dispensing fluid from the apparatus. A stop 199 is provided in the channel in such position that it engages the nozzle guard to prevent further reeling up of the hose when the desired position of the nozzle in the channel has been reached.

35 40 The opening 247 of the channel 195 is provided with a cover 201 which is hinged at 203 in such a manner that the hinge is accessible only from inside of the cover. An outwardly projecting funnel-like passage 207 is provided in said cover to receive and guide the protruding portion of the nozzle. Means are also provided so that the cover may be locked in closed position. This 45 is preferably accomplished by providing perforated ear 208 on said cover and a similar perforated ear 209 which is fixed to the housing 241. The ears are so positioned that their perforations will be in alignment when the cover is moved to closed position. By passing the bolt of a padlock 213 through the perforations, the cover is effectively locked in place. When the lock is removed, cover 201 will drop to a substantially vertical position to clear the projection 197 of the nozzle.

45 50 55 60 As shown in Figure 10, the channel 195 merges at its upper end with housing 241 so that no special closure is required other than that just described. An opening in housing 241 connects the housing with the channel to permit the hose to pass from one to the other.

The operation of the device is briefly as follows: Assuming that the pump has been locked up and that the lug 249 occupies the position shown in Figure 10, the operator will first unlock and remove the padlock 213 and swing the door or cover 201 to a position in which it will disengage the nozzle spout. By grasping the projecting portion 197 of the nozzle spout and exerting a tension thereon, the operator will withdraw a sufficient

amount of hose from the reel 243 to reach to the customer's receptacle. Unreeling of the hose causes the cam or lug 249 to move in a counter-clockwise direction (Figure 10) to engage the arm 179 on switch lever 251 and tilt the mercury switch to the "on" position. The lug 249 will pass arm 179 as additional hose is unreeled and as the cam again comes around to the switch operator it will turn the arm 181, which has been moved into the path of the cam by the actuation of arm 179, about pivot 183 against the action of spring 189' and pass beyond said arm which moves idly into place under action of the spring 189'.

5 10 15 The above described operation of switch 253 causes actuation of the motor 117 which in turn operates pump 115 to draw fluid through suction line 121 from the reservoir and place the liquid in the air release 119, meter 123, conduit 125, sight glass 127, conduits 131 and 245, reel 20 conduit 147 and hose 111 under pressure. The flow of fluid is not accomplished, however, until the operator depresses the nozzle valve, but when this occurs, the flow of fluid causes meter 123 to operate the clock mechanism 133 to register 25 the sale.

As soon as the required amount of fluid has been dispensed, the operator will close the nozzle valve, partially release the tension which up to this time he has been exerting on the hose and the latter will be retrieved under action of the spring 157 which tends to rotate said reel in the hose winding direction. When the nozzle guard engages the stop 199, only the aforesaid portion 197 of the nozzle spout will remain outside of 35 the channel or receptacle 195.

40 45 50 55 60 As the reel rotates to retrieve the hose, the lug or cam 249 moves in a clockwise direction (Figure 10). It will pass the arm 179 which was moved by the cam out of its path but it will engage the arm 181 which is not free to swing idly in the counter-clockwise direction, consequently the switch lever will be rotated until the cam passes over arm 181 and when this occurs the switch 177 will have been moved to circuit breaking position and the motor 117 and pump 115 will have been stopped. If more than one coil of hose has been removed from the reel, the cam will again pass the position of switch arm 251 and will engage the arm 179 which has been moved into the path of cam 179 by the depression of arm 181. However, the arm 179 is free to rotate in this direction about pivot 183 against the action of spring 189, hence the cam will pass by the arm 179 without further actuating the switch and when it has passed, the lever 179 will be pivoted in the opposite direction under action of spring 189 to its initial upright position so that it may be engaged and operated by the cam when the latter is again moved in a counter-clockwise direction.

65 70 75 80 85 To lock up the pump the operator merely swings the closure 201 in a clockwise direction (Figures 10 and 14). The portion 197 of the spout will follow the contour of the closure and project itself through the passage 207. When the perforations in ears 208 and 209 are in alignment the operator inserts the padlock 213 and locks it.

It should be noted that the tension on the spring 70 may be adjusted to vary the retrieving force exerted thereby, by loosening screw 163 and rotating the spring anchor 159 by means of handle 167 in the proper direction and again tightening the screw.

The time of operation of switch 253 may be varied by removing capscrew 173 and lug 249 from position in one of the openings 172 and inserting them in position relative to another of said openings. It may be noted that any adjustment of the lug from the position shown in Figure 10, which is just beyond the switch lever in the direction of unreeling rotation, will advance the time of opening of said switch.

10 It is thought that the invention and its numerous attendant advantages will be understood from the foregoing description, and it is obvious that numerous changes may be made in the form, construction, and arrangement of the several parts 15 without departing from the spirit or scope of the invention or sacrificing any of its attendant advantages.

Having thus described our invention, what we claim as new and desire to secure by United 20 States Letters Patent is:

1. In a dispensing apparatus, the combination of a hose terminating in a nozzle, means for supplying a flow of fluid to said hose, means upon which said hose may be stored and from which 25 it may be withdrawn by tension applied to the nozzle end of the hose, means operable automatically during the initial part of the withdrawing operation to render said flow supplying means operative, and means operable automatically 30 during the initial part of the storing operation to render said flow supplying means inoperative.

2. In a dispensing apparatus, the combination of a housing, a hose terminating in a nozzle, 35 means for supplying a flow of fluid to said nozzle, hose storing means in said housing, adapted to yield said hose in response to tension applied at the nozzle end thereof and to retrieve said hose when tension thereon is relaxed, and means 40 operable by said storing means to render said flow supplying means effective as hose is yielded and to render said flow supplying means ineffective as hose is retrieved.

3. In a dispensing apparatus, the combination 45 of a housing, a dispensing hose, a reel for said hose in said housing, flow supplying means, a conduit connecting said last named means with said reel, a conduit in said reel to which said hose is adapted to be connected, and means on said reel 50 cooperating with control devices for said flow supplying means, said devices being adapted to be operated by said means to render said flow supplying means effective when said reel is rotated in one direction and to render said flow supplying 55 means ineffective when said reel is rotated in the opposite direction.

4. In a liquid dispensing apparatus, including a dispensing hose, a housing, a hose storing device mounted in said housing, said device being 60 adapted to yield said hose when tension is applied to the latter, means operating said device to retrieve said hose when tension thereon is relaxed, and means for varying the effect of said operating means upon said device.

5. In a dispensing apparatus of the wet hose type, the combination of a hose adapted to be filled with fluid, means for maintaining said hose full of fluid, a device adapted to automatically retrieve and to store said hose in filled condition, 70 means for supplying a flow of fluid to said hose, control means for rendering said flow supplying means operable and means actuated as the first portion of said hose is withdrawn from said storing device for operating said control means.

6. In a dispensing apparatus, the combination

of a dispensing hose, a storing device therefor movable to yield or automatically retrieve said hose, said hose being constructed to maintain its fluid passageway open when it is stored on said device, mechanism for supplying a flow of fluid 5 to said hose, control means for said mechanism, an element mounted for movement by said hose storing device and adapted to operate said control means during the initial portions of its yielding and retrieving movements to render said 10 mechanism effective or ineffective.

7. In a liquid dispensing apparatus, a casing comprised of a lower housing and an upper housing having a projection disposed in overhanging relationship with said lower housing, a hose storing device mounted in said upper housing, an opening in the bottom of the projection of said upper housing, said projection and said opening being so arranged and disposed as to permit a free passage of said hose to and from said storing 20 device, and means for closing said opening to prevent unauthorized access to said hose.

8. In a dispensing apparatus, the combination of a rotatable hose reel, a hose connected to said reel and adapted to be stored thereon, fluid flow 25 supplying means connected to said reel, a switch for controlling said flow supplying means, a projection on said reel, and means connected with said switch and adapted to close it when contacted by said projection as the reel rotates in 30 one direction and adapted to open said switch when contacted by said projection as the reel rotates in the other direction.

9. In a dispensing apparatus, the combination 35 of a rotatable hose reel, a hose connected thereto and adapted to be wound upon or unwound from said reel as it rotates, means for supplying a flow of fluid to said hose, devices connected to control said flow supplying means, a projection mounted on said reel, and mechanism connected 40 to said devices and arranged in the path of said projection so that contact between said projection and said mechanism in one direction will cause said mechanism to actuate said devices and to be conditioned so that contact between said 45 projection and said mechanism in another direction will restore said mechanism which will in turn restore said devices to their original condition.

10. In a dispensing apparatus, the combination 50 of a hose terminating in a nozzle, means for supplying a flow of fluid to said hose, means operable for retrieving and storing said hose, said means being operable to yield said hose when tension is applied to the nozzle end thereof, and 55 means automatically operable during the initial stages of the yielding and retrieving operations for controlling the operation of said flow supplying means.

11. In a dispensing apparatus, the combination 60 of a hose, means for supplying a flow of fluid to said hose, control means for said flow supplying means comprising an actuator, means for storing said hose, said storing means being mounted for movement in repeated cycles to 65 yield said hose, an element connected to move with said hose storing means and adapted to contact and operate said actuator during the initial cycle of operation of said storing means, said actuator being mounted to permit said element to pass after being operated thereby and means for holding said actuator out of the path 70 of said element during the succeeding cycles of operation of said storing means.

12. In a dispensing apparatus, the combina- 75

- tion of a conduit, a spring biased device for storing said conduit, said conduit being adapted to maintain a passageway for fluid therethrough when stored on said device, means for supplying a flow of fluid to said conduit, control means for rendering said flow supplying means operable, and means actuated as the first portion of said conduit is withdrawn from storing device for operating said control means.
10. 13. In a fluid dispensing apparatus, the combination of a flexible dispensing conduit, a device for storing said conduit, said device being movable and comprising an element movable, therewith, means for supplying a flow of fluid to said conduit, a control device actuatable to render said flow device effective or ineffective, an actuator for said control device, means mounting said actuator for movement to one or the other of two positions, said actuator comprising means adapted to actively engage said element when said actuator occupies one position so that movement of said element will be transmitted to said actuator to move it to its other position, said engaging means being constructed to idly engage said element when said actuator occupies said other position.
14. In a fluid dispensing apparatus, the combination of a flexible dispensing conduit, a device for storing said conduit, said device being movable and comprising an element movable thereby in opposite directions as said conduit is yielded or retrieved, means for supplying a flow of fluid to said conduit, a control device actuatable to render said flow device effective or ineffective, an actuator for said control device, means mounting said actuator for movement to one or the other of two positions, said actuator comprising means adapted to actively engage said element, when said actuator occupies one position and said element moves in one direction, to cause said actuator to be moved to its other position by said element, said engaging means being adapted to idly engage said element when said actuator occupies its second position and the element continues its motion in the same direction, said engaging means being adapted to actively engage said element, when it moves in the opposite direction, to return said actuator to its initial position.
15. In a fluid dispensing apparatus, the combination of a flexible dispensing conduit, a device for storing said conduit, said device being movable and comprising an element movable thereby in opposite directions as said conduit is yielded or retrieved, means for supplying a flow of fluid to said conduit, a control device actuatable to render said flow device effective or ineffective, an actuator for said control device, means mounting said actuator for movement to one or the other of two positions, said actuator comprising means adapted to actively engage said element, when said actuator occupies one position and said element moves in one direction, to cause said actuator to be moved to its other position by said element, said engaging means being adapted to idly engage said element when said actuator occupies its second position and the element continues its motion in the same direction, said engaging means being adapted to actively engage said element, when it moves in the opposite direction, to return said actuator to its initial position.
16. In a fluid dispensing apparatus, the combination of a flexible dispensing conduit, a device for storing said conduit, said device being movable and comprising an element movable thereby in opposite directions as said conduit is yielded or retrieved, means for supplying a flow of fluid to said conduit, a control device actuatable to render said flow device effective or ineffective, an actuator for said control device, means mounting said actuator for movement to one or the other of two positions, two pawls pivotally mounted on said actuator, means for establishing an active station and an idle station for each pawl, said pawls being rotatable in opposite directions to their corresponding stations, said actuator being mounted for movement to position one or the other of said pawls in the path of said element as said actuator assumes one or the other of its positions, said pawls being arranged on said actuator so that the positioned pawl will remain at its active station and transmit motion of said element to said actuator in a direction to shift said actuator to the other of its positions but so that it moves to its idle position to permit free movement of said member in an opposite direction.
17. In a liquid dispensing apparatus adapted for use in connection with a service floor, a dispensing unit comprising a meter, a register connected to be driven by said meter, and a hose storing device, means for suspending said unit above said service floor, means situated at a point remote from said unit for supplying liquid thereto, a hose connected with said meter and adapted to be stored on said storing device, said device being movable to yield or to automatically retrieve said hose, remote control means for said liquid supplying means including a switch mounted on said unit, means for actuating said switch, and an operator mounted to be moved by said storing device for operating said switch actuating means so that said flow supplying means will be rendered effective as said hose is yielded and rendered ineffective as said hose is retrieved by said storing device.

tion and said element moves in one direction, to cause said actuator to be moved to its other position by said element, said engaging means being adapted to idly engage said element when said actuator occupies its second position and the element continues its motion in the same direction, said engaging means being adapted to actively engage said element, when it moves in the opposite direction, to return said actuator to its initial position, said engaging means being also adapted to idly engage said element as the latter continues its movement in said opposite direction after returning said actuator to its initial position.

18. In a fluid dispensing apparatus, the combination of a flexible dispensing conduit, a device for storing said conduit, said device being movable and comprising an element movable thereby in opposite directions as said conduit is yielded or retrieved, means for supplying a flow of fluid to said conduit, a control device actuatable to render said flow device effective or ineffective, an actuator for said control device, means mounting said actuator for movement to one or the other of two positions, two pawls pivotally mounted on said actuator, means for establishing an active station and an idle station for each pawl, said pawls being rotatable in opposite directions to their corresponding stations, said actuator being mounted for movement to position one or the other of said pawls in the path of said element as said actuator assumes one or the other of its positions, said pawls being arranged on said actuator so that the positioned pawl will remain at its active station and transmit motion of said element to said actuator in a direction to shift said actuator to the other of its positions but so that it moves to its idle position to permit free movement of said member in an opposite direction.

19. In a liquid dispensing apparatus adapted for use in connection with a service floor, a dispensing unit comprising a meter, a register connected to be driven by said meter, and a hose storing device, means for suspending said unit above said service floor, means situated at a point remote from said unit for supplying liquid thereto, a hose connected with said meter and adapted to be stored on said storing device, said device being movable to yield or to automatically retrieve said hose, remote control means for said liquid supplying means including a switch mounted on said unit, means for actuating said switch, and an operator mounted to be moved by said storing device for operating said switch actuating means so that said flow supplying means will be rendered effective as said hose is yielded and rendered ineffective as said hose is retrieved by said storing device.
